UNITED STATES PATENT OFFICE.

LEONARD ERIC SUNDSTROM, OF ROCKVILLE, NEBRASKA.

TIMER.

Application filed August 10, 1926. Serial No. 128,413.

This invention aims to provide a timer wherein the disadvantages incident to a wiping contact will be avoided through the instrumentality of a novel jump-spark mechanism.

It is within the province of the disclosure to improve generally and to enhance the utility of devices of that type to which the invention appertains.

10 With the above and other objects in view which will appear as the description proceeds, the invention resides in the combination and arrangement of parts and in the details of construction hereinafter described 15 and claimed, it being understood that changes in the precise embodiment of the invention herein disclosed, may be made within the scope of what is claimed, without departing from the spirit of the invention.

20 In the drawings:—

Figure 1 shows in elevation, a device constructed in accordance with the invention, a part being omitted, and the circuits being shown diagrammatically.

25 Figure 2 is a section of the device delineated in Figure 1; and

Figure 3 is a fragmental elevation disclosing a slight modification.

The numeral 1 marks a portion of the 30 frame of an internal combustion engine, the frame having a recess 2. The cam shaft appears at 3. The numeral 4 designates a timer casing extended into the recess 2, a spacing washer 5 being interposed between 35 the rear end of the timer casing 4 and the frame 1, to receive the wear which occurs when the timer casing is rocked by the usual means (not shown), connected to a lip 6 on the timer casing 4.

40 The rim of the casing 4 has circumferentially spaced main terminals 7. The rim of the timer casing 4 carries auxiliary terminals 8 located near to the main terminals 7, but spaced far enough therefrom, so that a 45 spark cannot jump between the terminals 7 and 8. The numeral 9 designates an arm, a conducting member 10 being mounted on one side of the arm near to the outer end of the arm. Any suitable means may be supplied 50 for mounting the arm 9 on the cam shaft

3. As shown, the cam shaft has a cross pin 11 received at its ends, in notches 11^a formed in the end of a collar 14 which carries the arm 9, one end of the collar 14 being engaged by an abutment or nut 15 on the cam shaft 3, and the outer end of the collar 14 be-

ing engaged by a nut 12 threaded on the cam shaft. The nut 12 is omitted in Figure 1.

The device as above described may be used in a variety of ways, and the circuits employed will depend upon the taste and judgment of the persons doing the wiring and installing. By way of illustration, in Figure 1, there is shown the primary winding 16 of a coil 17, a switch 18 being interposed 60 in the winding 16, and a source 19 of electrical energy being interposed in the winding 16. The winding 16 may be grounded at its ends, as shown at 20. The secondary winding of the coil 17 is denoted by the numeral 21 and may be grounded at one end, as shown at 22. On the other end of the secondary winding 21, branches 23 lead to the main terminals 7. From the auxiliary terminals 8, conductors 24 lead to the spark 65 plugs 25, the usual engine ground being designated by the numeral 26.

In practical operation, the high tension current enters by means of the branch 23 and passes into the main terminal 7. When the 70 arm 9 moves around into the position shown in Figure 1, the current jumps from the main terminal 7 to the conducting member 10, and jumps from the conducting member 10, to the auxiliary terminal 8, the current proceeding 75 thence to the spark plug 25, by way of the conductor 24.

In Figure 3, a slight modification is shown in the means whereby the arm is connected to the cam shaft. In Figure 3, the cam shaft 80 is marked by the numeral 27 and carries an abutment 28 provided with ribs 29 received in grooves 30 on an arm 31 detachably mounted on the cam shaft 27, the arm 31 corresponding to the arm 9, and carrying a conducting member 32, represented in Figure 1 by the conducting member 10. The arm 31 has ribs 33 received in grooves 34 formed in the rear surface of a washer 35 on the cam shaft 27, the washer 35 having seats 38 85 receiving the ends of the cross pin 36 in the cam shaft 27, a nut 37 being threaded on the cam shaft 27 and serving to bind the washer 35 and the arm 31 together, the arm engaging the abutment 28.

100 What is claimed is:—

In a device of the class described, a casing, terminals carried by the casing and located in one plane, a shaft supported for rotation, an arm movable in a plane parallel to and spaced from the plane in which the terminals are located, the arm having a laterally off-

set conducting member adapted to engage the terminals, an abutment on the shaft, a washer on the shaft, the abutment having a rib, the washer having a groove, the arm being mounted on the shaft between the washer and the abutment and having a groove receiving the rib of the abutment, the arm having a rib received in the groove of the washer, the provision of a rib on both

the abutment and the arm preventing a reversal of the arm and a consequent displacement of the conducting member with respect to the terminals, and means for holding the washer, the arm, and the abutment, together.

In testimony that I claim the foregoing as my own, I have hereto affixed my signature.

LEONARD ERIC SUNDSTROM.
